UNITED STATES PATENT OFFICE.

CHARLES L. BASTIAN, OF CHICAGO, ILLINOIS, ASSIGNOR, BY MESNE ASSIGNMENTS, TO BOTTLERS MACHINERY MANUFACTURING COMPANY, OF CHICAGO, ILLINOIS, A CORPORATION OF ILLINOIS.

VALVE FOR COUNTER-PRESSURE BOTTLE-FILLING MACHINES.

No. 833,365.

Specification of Letters Patent.

Patented Oct. 16, 1906.

Application filed April 12, 1905. Renewed September 7, 1906. Serial No. 333,715.

To all whom it may concern:

Be it known that I, CHARLES L. BASTIAN, a citizen of the United States, residing at Chicago, in the county of Cook and State of Illinois, have invented certain new and useful Improvements in Valves for Counter-Pressure Bottle-Filling Machines, of which the following is a specification.

My invention relates to the art of counter-pressure bottle-filling machines wherein the bottles are filled with a liquid which is maintained during the entire filling operation subject to the influence of pneumatic pressure in order to check bubbling and foaming and insure the filling of the bottle with the solid liquid.

Among the salient objects of the invention are to provide an improved valve mechanism whereby the bottle may be filled with great celerity and despatch; to provide a mechanism wherein the degree of pressure maintained in the bottle during the filling operation may be nicely regulated to such a degree as will serve to keep down foaming in each case, differently-charged liquids requiring different degrees of pressure for such purpose; to provide a valve mechanism wherein the discharge accompanying the snifting operation may be controlled and saved, thus rendering the machine less sloppy in operation and more economical when working upon valuable liquors; to provide a valve mechanism which may be readily adjusted to accommodate varying sizes of bottles—such as quarts, pints, and splits—and generally to provide an improved valve mechanism of the type designated which shall be entirely automatic in its action and reliable in its workings.

To these and other minor ends my invention consists in a novel valve mechanism for machines of the character specified possessing the novel feature of construction and mode of operation substantially as herein-after described, and definitely pointed out in the appended claims.

The valve mechanism of my present invention is capable of application and advantageous employment generally in bottle-filling machines of that type employing a head or tank containing the liquid to be filled under pressure, one or more filling-valves depending therefrom, and means for lifting the

empty bottles into registering engagement with said valves; but in order to render the function and operation of my improved valve mechanism entirely clear I have chosen to illustrate the same in connection with a bottle-filling machine of the general type above referred to on which I have heretofore, on the 13th day of February, 1905, filed an application for Letters Patent, Serial No. 245,522.

Referring to the accompanying drawings, which illustrate my invention in a preferred mechanical form, Figure 1 is an elevational view, mainly in central vertical section, of a machine to which my improvements are well adapted. Fig. 2 is a similar view, on an enlarged scale, of the valve mechanism proper. Fig. 3 is a view, partly in elevation and partly in vertical section, of the parts shown in Fig. 2 in a plane at right angles to the plane of the latter figure. Fig. 4 is a top plan view of Fig. 3, and Fig. 5 is a side elevational view corresponding to Fig. 3 and more particularly illustrating an extension feature of the mechanism whereby it is adapted to cooperate with bottles of varying sizes.

Referring to the drawings, and first briefly describing the general features of the filling machine in which I have shown my present improvements embodied, 10 designates a circular base-plate, on which is rigidly mounted a stationary pedestal, comprising a hollow circular base member 11 and a vertical cylindrical member 12, which is annularly cored to form a compressed-air reservoir 13 and a central sleeve 14, that constitutes an extended bearing for the lower portion of a main upright shaft 15, stepped centrally on the base-plate 10, preferably by means of anti-friction-bearings, (indicated at 16.) Resting on the upper end of the upright shaft 15 is a circular head in the form of a tank 17, closed by an air-tight lid or cover 18. The upper portion of the shaft 15 has one or more longitudinal feathers 19 and beneath the latter a threaded portion 20. Secured to the under side of the tank 17 centrally thereof is a depending sleeve 21, which surrounds the shaft 15 and has one or more grooves engaging the feather or feathers 19. On the lower end of the sleeve 21 is rotatably secured a nut 22, internally threaded to engage the threaded portion 20 of the shaft, by rotating which nut 105 the tank may be raised or lowered relatively

to the upper end of the shaft 15 while still maintaining its driven relation to the latter. Surrounding and connected to the shaft 15, as by a set-screw 23, is a sleeve 24, extending 5 radially from which are a series of arms 25, each carrying a cylindrical holder 26, in which is secured a cylinder 27. In each of the cylinders 27 is a piston or plunger 28 on the lower end of a piston-rod 29, the upper 10 end of which latter carries a shoe 30, adapted to support a bottle 31. Surrounding the shaft 15, between the upper end of the pedestal and the lower end of the sleeve 24, are a pair of annular-ported valve members, the 15 lower of which (designated by 32) is stationary, being secured to the top of the pedestal, and the upper of which (designated by 33) is rotary, being driven from the sleeve 24 by coöperating vertical lugs 34 and 35 on said 20 parts, respectively. From the rotary valve member 33 extend a series of suitably-bent pipes 36, serving to conduct compressed air to and from the air-lift cylinders 27.

The lower stationary valve member 32 is 25 provided with an inlet air-passage 32' and an outlet air-passage 32'', both of which are arc-shaped. To the inlet-passage 32' air is admitted from the reservoir 13 through a port x , and from the exhaust-passage 32'' air is 30 discharged through a port z . The inlet-passage 32' communicates through a port x' with ports y in the upper rotary valve member, the latter ports communicating with the pipes 36, and these ports y communicate through port 35 y' with the exhaust-passage 32''. When a port y in the upper rotary valve member registers with the port x' in the lower stationary valve member, air will flow into the cylinder connected by the pipe 36 with said port y to 40 raise the bottle, and when this port y during the rotation of the upper valve member registers with the port y' in the lower stationary valve member the air in the lift-cylinder will escape through the exhaust-port z . 45 The cover 18 of the tank-head has a centrally-disposed fluid-inlet pipe 37, which extends to within a short distance of the bottom of the tank, and is further provided with a short tube 38 set therein, adapted to permit 50 the discharge of air as the liquid enters up to a certain point, said tube being provided on its lower end with a valve-seat 38^a, and in the tank is a hinged float 39, which carries a valve 40, adapted to close and open said 55 valve-seat on the rise of the fluid, and thereby confine the body of air remaining in the tank above the liquid, and thus by creating a pressure equal to the hydrostatic head of the incoming liquid to thereby arrest the inflow 60 of such liquid until the height in the tank is lowered by the filling of the bottles. Into this space air discharged from the bottles flows, and such excess is relieved automatically as the liquid falls, since the falling of 65 the float retracts the valve from its seat,

thereby allowing a fresh flow of liquid to the tank until a like condition of balance is again reached.

The base of the tank 17 has an annular series of openings 17^a formed therethrough, which are covered by the bottle-filling valve mechanism constituting the subject-matter of the present invention and next to be described. This mechanism, which is more fully shown in the detail views, Figs. 2 to 5, inclusive, consists of the following: 41 designates a plate that may be secured to the base of the tank in a fluid-tight manner, as by means of screws or bolts 42. Depending from the plate 41 are a pair of parallel suspension-rods 43, having heads or nuts 44 on their lower ends, on which is slidably supported by apertured lateral ears 45 a valve-block 46. The plate 41 and valve-block 46 are centrally apertured to slidably fit a tube 47, mounted therein and packed against leakage by suitable stuffing-boxes 48 and 49. Between the glands of said stuffing-boxes is interposed a compression coil-spring 50, and fast on the tube 47 inside the spring 50 is a 90 collar 51, constituting a lower abutment for an inner smaller coil-spring 52, the upper end of which also abuts against the gland of the upper stuffing-box 48. The upper end of the tube 47 is surmounted by a valve plate or 95 disk 53, the lower operative face of which is provided with a fibrous or other packing-ring 54, immediately beneath which the walls of the tube 47 are provided with one or more ports 55. The valve-block 46 is cored to 100 form a series of valve-controlled passages and ducts which control the passage of compressed air from the head or tank 17 into the bottles and the egress of such compressed air from the latter as the bottles are filled, substantially as follows: 56 and 57 designate a 105 pair of vertical passage-ways arranged on diametrically opposite sides of the central tube 47, in the former of which is inserted a vein-valve 58 and in the latter a plug-valve 110 59, having an operating-handle 60. The lower ends of the passage-ways 56 and 57 both connect, by horizontal ducts 61 and 62, respectively, with a central vertical annular opening 63, extending through the lower end 115 of the valve-block and surrounding the central tube 47. Behind and between the vertical passage-ways 56 and 57 is cored a vertical cylindrical chamber 64, Figs. 3 and 4, in which is a rod 65, having fast thereon a pair of 120 piston-heads 66 and 67, separated by a sleeve 65' on said rod. Said rod 65 extends above the valve-block and is provided on its upper end with a head or nut 68, which engages the bottom of the tank 17. On the rod 65 and 125 between its head 68 and a cross-piece 64, fitted in the upper end of the cylinder 64, is a coil-spring 69 normally tending to maintain the pistons 66 and 67 in the elevated position shown in Fig. 3 and the head 68 in contact 130

with the bottom of the tank. The casing or cylinder of the cylindrical chamber 64 has laterally-projecting nozzles 70 and 71, the former of which has an axial duct 72 tapping the cylindrical chamber substantially midway of its length, while the latter has an axial duct 73 tapping said chamber at its lower end.

From the chamber 64, at a point slightly below the inlet of the duct 72 thereto, extend ducts 74 and 75, Fig. 4, the former leading to the upper end of the vein-valve 58 and the latter to the upper end of the vertical passage 57 above the plug-valve 59. The inlet-nozzle 70 is connected by a flexible hose 76, Fig. 1, with the interior of the tank 17 at or near its upper end, while the discharge-nozzle 72 has attached thereto a similar flexible hose 77, that depends therefrom and debouches into an annular trough 78, secured to the central pedestal 12 substantially opposite the lower ends of the air-cylinders 27. The lower end of the valve-block 46 has an externally-threaded depending flange 46^a, within which is secured an annular rubber gasket 79, confined in place by a ring 80, screwed into the flange 46^a.

The lower face of the gasket and the opening of the ring are beveled or concaved, as shown in Fig. 2, to form a suitable seat for air-tight engagement with the upper end of a bottle, and in order to insure the entrance of the tubes 47 into the necks of the bottles, as well as to accurately guide the latter into perfect registration with the valve-seat, I preferably employ a bell 81, carried by a bracket 82, that is mounted to slide freely on a vertical rod 83, that passes through apertures in upper and lower lugs 82^a and 82^b of the bracket, said rod 83 being removably secured at its upper and lower ends to the base of the tank and the revolving bottle-carrier, respectively. The upper contracted end of the bell 81 is axially apertured to receive the depending filling-tube 47, the bell passing over said tube as it rises. The opening in the upper end of the bell is of somewhat greater diameter than the upper end of the neck of the bottle, so that the latter in registering with the valve-seat passes entirely through the bell, engaging the latter by the sides of the neck, as shown at the right in Fig. 1.

The operation of the machine, briefly described, is as follows: Assuming that the air-reservoir 13 is charged with compressed air (which may be effected by means of an air-pump 13', indicated in Fig. 1 and more particularly disclosed in the application hereinbefore referred to, or by any other convenient means) and that the machine is otherwise in condition for operation, the liquid to be filled is allowed to flow into the tank and, raising the float 39 and closing the valve 40, compresses the air above its surface to a degree of pressure equaling the hydrostatic

head or pressure of the liquid at its source of supply. The pistons 66 and 67 of the valve mechanism being in the relative positions shown in Fig. 3, the compressed air in the tank is held against escape so long as the bottle-filling valve mechanism is in its lowermost position shown therein. The shoes of the air-lifts being supplied with bottles and the machine being started in operation, as soon as each of the ducts of the upper revolving air-valve member 33 passes into registration with the inlet-port of the lower stationary valve member 32 the compressed air from the reservoir flows instantly through the tube 36 to the under side of the piston 28, causing the latter to rise, carrying with it the superposed bottle 31. As soon as the neck of the bottle engages the bell 81 it is centered by the latter, (if not previously in true axial alignment with the valve-tube 47,) whereupon the bell is carried upwardly on its sliding support, the lower end of the tube 47 entering the neck of the bottle. As soon as the upper end of the bottle contacts the elastic gasket 79 of the filling-valve mechanism the valve-block begins to rise on top of the bottle, being guided by the suspension-rods 43, on which it slides. As soon as the valve-block has risen sufficiently to lower the piston 67 to a point beneath the lateral ducts 74 and 75 the inlet-passage 72 is placed in communication with said ducts, whereupon the compressed air above the fluid in the head or tank passes freely and quickly through the duct 74, vein-valve 56, duct 61, and annular passage 63 to the interior of the bottle, the compressed air to a more limited extent also finding its way through the ducts 75, 57, and 62 to the annular passage 63 and the interior of the bottle, the extent of the latter flow depending upon the extent to which the plug-valve 59 is set to throttle and limit the flow. In this manner equilibrium of pressure in the head and bottle is quickly established before the flow of liquid begins. On the still further upward rise of the valve-block 46 the gland of the lower packing-box 49 strikes the collar 51, which is fast on the tube 47, and raises the valve 53, thus allowing flow of the liquid to be charged into the bottle through the opening or openings 55 and the interior of the tube. By reason of the described equilibrium of pressure in the tank and bottle this flow occurs solely by gravity, which, together with the condensed condition of the air surrounding said liquid, eliminates the bubbling and foaming that would otherwise occur or reduces it to a minimum. The function of the plug-valve 59 is to regulate and restrict the speed of the air-discharge from the bottles on the liquid commencing to flow, and by thus impeding the fall or flow of the liquid to still further prevent foaming, providing, in fact, a mechanical means of retarding the flow in addition to the physical means

provided by the establishment of equal pressure in the tank-head and bottles, since by throttling down the air-egress passage sufficiently a greater pressure can be created in the bottles than exists in the head, (due to the gravity effect of the liquid in addition to the pneumatic pressure in the head.) By the time each bottle is fully charged with liquid the air-lift cylinder has been carried out of communication with the inlet or compressed air and into communication with the exhaust, whereupon the bottle-lift begins to descend. With the descent of the valve-block 46 (forced downwardly by the spring 50) and just before the bottle breaks its connection with the valve-seat 79 the lower piston 67 uncovers the mouth of the duct 75, thus permitting such air or gas pressure as remains in the neck of the bottle to blow out by a quick movement through the passages 63 62 57, port of the plug-valve 59, passage 75, cylinder 64, and exhaust-passage 73 into the drip-tube 77, thus effecting the snifting of the bottle. So much of the fluid as is thus blown off in the final operation is directed by the drip-tube 77 into the stationary trough 78, from which latter it may be discharged or withdrawn as desired, such residue in the case of valuable liquors being saved and returned to the original source of supply. Each bottle while undergoing the above-described operation travels around approximately three-quarters of a single revolution of the machine, the filled bottles being withdrawn from the shoes of the air-lifts in succession either by hand or automatically by means of a star-wheel 85, herein indicated as lying across the path of said bottles, such star-wheel and its operating mechanism being described in my former application hereinbefore referred to.

The vertical adjustability of the head or tank relative to its supporting-standard by means of a nut 22 and threaded portion of the standard provides for unevennesses or irregularities in the heights of the bottles to be filled. My improved valve mechanism is also provided with means whereby it may be employed in the filling of bottles of widely-varying sizes, such as quarts, pints, and splits. The adaptation of said valve mechanism to this function is illustrated more particularly in Fig. 5. The mechanism as shown in Fig. 2 may be assumed to adapt the machine for the filling of quart bottles. To effect the filling of pint bottles, the ring 80 may be removed from the lower end of the valve-block and substituted by an extension member 84, having on its upper end a ring 80^a, screwing onto the lower end of the valve-block and having its lower end formed and equipped in all respects similar to the lower end of the valve-block, as plainly shown in Fig. 5. For the filling of half-pint bottles or 65 "splits" a similar extension member, but of

greater length, may be employed, as indicated by dotted lines in Fig. 5.

The leading advantages of the bottle-filling valve mechanism hereinabove described are, first, that it produces a very rapid equalization of pressure between the head and the bottle as soon as the latter is registered therewith, thus requiring a minimum delay in the flow of the liquid to the bottle; secondly, by means of the plug-valve the air seeking to escape from the bottle as the liquid enters may be throttled down to any desired extent, such as experiment may prove necessary in each case to increase the pressure and retard the flow, and thus keep down bubbling and foaming of the liquid; thirdly, it effects a snifting of the bottles before the latter are released from engagement therewith, thus eliminating the sloppy condition that usually characterizes machines of this type, besides effecting a considerable economy in the case of valuable liquors in the conservation of that portion discharged in the snifting operation.

It being evident that the specific details of the mechanism as herein shown and described might be considerably modified and varied by those skilled in the art without departing from the true principle of the invention or sacrificing any of the advantages thereof I do not limit myself to the particular mechanical embodiment of the invention herein shown, except to the extent indicated by specific claims.

I claim—

1. In a counter-pressure filling-machine, the combination with a liquid-tank and a filling-tube depending therefrom, of a movable valve-block surrounding said filling-tube and having formed therein an air-passage divided into two separate branches, each branch communicating at one end with the tank and at the other end with the article to be filled, a check-valve in one branch of said air-passage, a throttle-valve in the other branch, and a cut-off valve in said valve-block normally closing said air-passage but operable upon the rise of the valve-block to open the same.

2. In a counter-pressure filling-machine, the combination with a liquid-tank and a filling-tube depending therefrom, of a movable valve-block surrounding said filling-tube and having formed therein a divided air-passage communicating at one end with the tank and at the other end with the article to be filled, a check-valve in one branch of said air-passage, a throttle-valve in the other branch, and a stationary cut-off valve in the valve-block intersecting and normally closing said air-passage but operable upon the rise of the valve-block to open the same.

3. In a filling-machine, the combination of a liquid-tank, a filling-tube depending therefrom, a liquid-valve, a movable valve-

block surrounding said filling-tube, a normally closed air connection between the tank and the bottle being filled, and relatively fixed means for opening said air connection when the valve-block is moved upward.

4. In a filling-machine, the combination of a liquid-tank, a filling-tube depending therefrom, a liquid-valve, a movable valve-block surrounding said filling-tube, a normally closed air connection between the tank and the bottle being filled, said valve-block having a chamber in said air connection, a piston in said chamber and normally closing said air connection, a rod carrying said piston and arranged to hold the piston in fixed position as the valve-block moves upward to thereby open the air connection, and a spring holding said rod and piston in fixed position on the downward movement of the valve-block.

5. In a counter-pressure filling-machine, the combination with a liquid-tank, of a vertically-inovable valve-block depending therefrom and having formed therein an air-passage divided into two branches, each branch 25 communicating at one end with said tank and at the other end with the article to be filled, a cut-off valve in said valve-block operable to open the air-passage when the valve-block is raised, a check-valve in one 30 branch of said air-passage, a throttle-valve in the other branch thereof, a vertically-movable filling-tube depending from said tank and slidably engaging said valve-block, a valve on the upper end of said filling-tube 35 controlling the flow of liquid to and through the latter, and means whereby said filling-tube and its valve are raised by said valve-block during the upward movement of the latter.

6. In a counter-pressure filling-machine, the combination with a liquid-tank, of a vertically-movable and valve-controlled filling-tube depending therefrom, a vertically-movable valve-block surrounding said filling- 45 tube, said valve-block being provided with a

valved air-passage to communicate the pressure in the tank to the article to be filled, and with a snifting-passage communicating with said air-passage, and means for causing said article to engage and raise said valve-block and thereby open the filling-tube and said passages.

7. In a counter-pressure filling-machine, the combination with a liquid-tank, and a valve-controlled filling-tube depending therefrom, of a vertically-movable valve-block surrounding said filling-tube, said valve-block being provided with an air-passage divided into two branches, each branch communicating at one end with said tank and at the other end with the article to be filled, and also with a snifting-passage communicating with said air-passage, a check-valve in one branch of said air-passage, a throttle-valve in the other branch thereof, and a cut-off 65 valve controlling both said air-passage and said snifting-passage.

8. In a counter-pressure filling-machine, the combination with a liquid-tank, and a valve-controlled filling-tube depending therefrom, of a vertically-movable valve-block surrounding said filling-tube, said valve-block being provided with a divided air-passage communicating at one end with said tank and at the other end with the article to be filled, and also with a snifting-passage communicating with said air-passage, a check-valve in one branch of said air-passage, a throttle-valve in the other branch thereof, and a cut-off valve which, in the lowest position of the valve-block closes said air-passage and opens said snifting-passage, and in the raised or filling position of said valve-block opens said air-passage and closes said snifting-passage.

CHARLES L. BASTIAN.
